COMBINED SILL BRACE AND DRAFT GEAR
STOPEdmund D. Campbell, New York, N. Y., assignor to
American Car and Foundry Company, New
York, N. Y., a corporation of New Jersey

Application February 19, 1944, Serial No. 523,057

8 Claims.

(Cl. 213—51)

This invention relates to combined center sill braces and draft gear stops of the prefabricated type.

Castings have generally been used in the past for center fillers and draft gear stops but with the advent of high tensile steels attention has been directed to reducing the weights of cars. Castings are necessarily heavy due to the necessity of large radii and low strength value of the metal. The minimum weight arrangement is, of course, one in which the component parts of the center filler and draft gear stops are directly welded to the center sills so that the forces are directly transmitted thereto, but such welded constructions can not be repaired in case of damage without practically rebuilding the car. It is an object, therefore, of the present invention to provide a combined sill brace and draft gear stop made up of rolled and plate members which may be prefabricated and applied as a unit to the car center sills.

A further object of the invention is the provision of a combined center sill brace and draft gear stop unit made up of a minimum number of easily obtained parts.

A still further object of the invention is the provision of a combined center sill brace and draft gear stop unit having the component parts so formed as to avoid the necessity of special or expensive dies.

These and other objects of the invention will be apparent to persons skilled in the art from a study of the following description and accompanying drawings, in which

Fig. 1 is a plan view of the improved unit applied to fabricated center sills;

Fig. 2 is a sectional view taken substantially on the longitudinal center line of Fig. 1;

Fig. 3 is a sectional view taken substantially on line 3—3 of Fig. 1, and

Fig. 4 is a sectional view similar to Fig. 3 but showing a slight modification.

Referring now to the drawings in detail, it will be seen that the improved unit has been shown as applied to center sills of the fabricated or fish belly type. The center sills, as clearly shown, are formed of web plates 2, top angular chord members 4 and inner and outer angular bottom chord members 8 and 10 respectively. The top chord members are joined together by a plate 12 which may be either the car floor or the bolster top cover plate, dependent upon the type of car.

The combined sill brace and draft gear stop unit, as clearly shown in Figs. 1, 2 and 3, is formed in part by rolled angle members 14 of unequal

flange lengths. The long flanges 16 are adapted to closely contact the web plates 2 of the center sills, while the short flanges 18 are directed inwardly toward each other. The flanges 18 have connected thereto as by welding vertically extending flanges 20 of angular shaped pressings made from plate metal. The horizontal flanges 22 of these angular shaped pressings are directed inwardly and attached together by means of a filler plate 24 to which they are securely welded. Flanges 20 and 22 are of such length and so positioned as to closely contact the flanges of bottom chord angle 8, while filler 24 is of such thickness as to have its outer surface substantially flush with the outer angles of chords 8 and 10. The filler plate and chord angles 8 and 10 have their outer surfaces in a substantially common plane in order that they may receive and closely engage either the bolster bottom cover plate or a center bearing plate, neither of which are shown. The forward ends of unequal angles 14 and the angular pressings are located substantially in a common vertical plane and have securely attached thereto as by welding draft gear back stops 26. These stops are backed up by flanges 16 and 18 of the rolled angles and by flanges 20 and 22 of the angular pressings. However, in order to additionally reinforce these stops small horizontally extending ribs 28 and 30 are securely welded to the back stops and to flanges 16 at the top and intermediate portions respectively.

In order to additionally tie the rolled angles and angular pressings together and provide a king pin guide, transversely extending tie plates 32 are securely welded to flanges 16, 18, 20 and 22 as well as to semi-cylindrical members 34. These semi-cylindrical members are joined together by means of longitudinally extending buttress plates 36 interposed between and welded to the semi-cylindrical members and to the filler plate 24. The semi-cylindrical members 34 may be formed by pressing or they may be cut from tube sections, or, if desired, a complete tubular member may be used, in which case the buttressing plates would be butt-welded thereto as are the tie plates 32. It will be obvious that the rolled angles and angular pressings, as well as the remaining parts of the unit may be securely welded together and the entire unit applied to the center sills and held in place by any suitable means such as rivets 40. It will also be obvious that where car capacities require larger or smaller center sill chord angles 8, the angular pressings may be readily modified and their position

of attachment to flanges 18 changed so as to accommodate changed bottom chords.

Considerable welding may be avoided by utilizing a rolled channel member as shown in Fig. 4. In this form the channel web 42 is adapted to closely contact and subsequently be secured to center sill webs 2, while the top and bottom flanges 44 and 46, respectively, are directed toward each other. When using the channels the same angular pressings and filler of Fig. 3 may be used if desired, but a certain amount of welding may be eliminated if the inner edges of flanges 22 are depressed as at 48 so as to bring the outer surface 50 substantially into the plane of the bottom chords 8 and 10 for reception of the center bearing or bolster bottom cover, whichever is used. In this case the inner edges of flanges 22 are directly welded together instead of being welded to a filler plate as shown in Fig. 3. The king pin guide arrangement is identical with that previously described with the exception that the transversely extending tie plates 52 are of slightly less height than the tie plates 32 of Fig. 3. Also the buttressing plates 36 will be welded directly to the inner edges of flanges 22 instead of to the filler plate. It will, of course, be obvious that the modified angular pressings of Fig. 4 may be used with the rolled angles of Fig. 3 if desired. With the construction of Fig. 4 the draft gear back stops 26 are backed up by flanges 20 and 22 of the angular pressings as well as by web 42 and flanges 44 and 46 of the rolled channel member. The portion of the back stop intermediate channel flanges 44 and 46 may be reinforced by buttressing ribs 56 securely welded to the webs of the channels and to the back surface of the draft gear stops.

It will be obvious from the preceding description that the unit may be formed of rolled and easily pressed metal sections connected together to accommodate various sizes and weights of chord angles 8. It will also be obvious that even if the bottom chords 8 were omitted, the same unit could still be used merely by shifting the point of attachment of flanges 18 and 20 and possibly lengthening flange 22. The unit could also be readily applied when so modified to AAR Z section center sills.

While the construction has been described more or less in detail with specific reference to two forms thereof, it will be obvious that other forms, modifications and rearrangements of parts may be made and all such modified forms and rearrangements of parts are contemplated as fall within the scope of the appended claims defining my invention.

What is claimed is:

1. In a car underframe, spaced apart center sill members formed with vertically extending webs, angle bars located adjacent the lower edge of the webs and having one flange of each secured to the inner side of said webs and the other flange directed inwardly toward the center of the sill, rolled members of angular cross-section secured to the inner sides of said webs above said angle bars, said rolled members including bottom flanges located in upwardly spaced substantially parallel relationship to said other flange of said angle bars, pressed metal plates of angular cross-section closely engaging the flanges of said angle bars and being weld connected to said bottom flanges of the rolled members in spaced relationship to said center sill webs, draft gear back stops overlapping and welded to the outer ends of said rolled members and pressed

metal plates, and reinforcing means secured to said back stops and rolled members rearwardly of said back stops.

2. In a car underframe, spaced apart center sill members formed with vertically extending webs, angle bars located adjacent the lower edge of the webs and having one flange of each secured to the inner side of said webs and the other flange directed inwardly toward the center of the sill, rolled members of angular cross-section secured to the inner sides of said webs above said angle bars, said rolled members including bottom flanges located in upwardly spaced substantially parallel relationship to said other flange of said angle bars, pressed metal plates of angular cross-section closely engaging the flanges of said angle bars and being weld connected to said bottom flanges of the rolled members in spaced relationship to said center sill webs, draft gear back stops overlapping and welded to the outer ends of said rolled members and pressed metal plates, reinforcing means secured to said back stops and rolled members rearwardly of said back stops, and means connecting said rolled members and pressed metal plates together rearwardly of said reinforcing means and including a king pin guide.

3. In a car underframe, spaced apart center sill members formed with vertically extending webs, angle bars located adjacent the lower edge of the webs and having one flange of each secured to the inner side of said webs and the other flange directed inwardly toward the center of the sill, rolled members of channel cross-section having their webs secured to the inner sides of said center sill webs with the bottom flanges directed inwardly in upwardly spaced parallel relationship to said other flange of said angle bars, pressed metal plates of angular cross-section closely engaging the flanges of said angle bars and being weld connected to the bottom flanges of said rolled members of channel cross-section, and draft gear back stops overlapping and weld secured to the outer ends of said rolled members and secured to the outer ends of said rolled members and pressed metal plates.

4. In a car underframe, spaced apart center sill members formed with vertically extending webs, angle bars located adjacent the lower edge of the webs and having one flange of each secured to the inner side of said webs and the other flange directed inwardly toward the center of the sill, rolled members of channel cross-section having their webs secured to the inner sides of said center sill webs with the bottom flanges directed inwardly in upwardly spaced parallel relationship to said other flange of said angle bars, pressed metal plates of angular cross-section closely engaging the flanges of said angle bars and being weld connected to the bottom flanges of said rolled members of channel cross-section, draft gear back stops overlapping and weld secured to the outer ends of said rolled members and pressed metal plates, and reinforcing means secured to said back stops and rolled members intermediate the flanges thereof thereby assisting said flanges in holding said back stops in position.

5. In a car underframe, spaced apart center sill members formed with vertically extending webs, angle bars located adjacent the lower edge of the webs and having one flange of each secured to the inner side of said webs and the other flange directed inwardly toward the center of the sill, rolled members of channel cross-section having their webs secured to the inner sides of said center sill webs with the bottom flanges directed

inwardly in upwardly spaced parallel relationship to said other flange of said angle bars, pressed metal plates of angular cross-section closely engaging the flanges of said angle bars and being weld connected to the bottom flanges of said rolled members of channel cross-section, draft gear back stops overlapping and weld secured to the outer ends of said rolled members and pressed metal plates, and transversely extending brace means secured to said rolled members of channel cross-section and to said pressed metal plates and rigidly connecting the same rearwardly of said back stops.

6. As an article of manufacture, a combined sill brace and draft gear back stop support comprising spaced channels arranged with the top and bottom flanges thereof directed horizontally toward each other, a plurality of metal plates of angular cross-section each having one leg directed vertically and welded to the outer surface of the bottom flange of the adjacent channel in inwardly spaced relation to the plane of the web, means connecting said plurality of metal plates together, and back stops overlapping and secured to the ends of said channels and metal plates, said back stops being held by the top and bottom flanges of said channels in a plane substantially normal to the planes of the channel webs.

7. As an article of manufacture, a combined sill brace and draft gear back stop support comprising spaced channel form members arranged with the top and bottom flanges thereof directed horizontally toward each other, a plurality of metal plates of angular cross-section each having

5 one leg directed vertically and welded to the outer surface of the bottom flange of the adjacent channel form members in inwardly spaced relation to the plane of the web, means connecting said plurality of metal plates together, back stops overlapping and secured to the ends of said channel form members and metal plates, said back stops being held by the top and bottom flanges of said channel form members in a plane substantially normal to the planes of the webs, and plate metal brace means rigidly joining said channels and metal plates rearwardly of said back stops, said brace means including a king pin guide.

15 8. As an article of manufacture, a combined sill brace and draft gear back stop support comprising spaced channels arranged with the top and bottom flanges thereof directed horizontally toward each other, a plurality of metal plates of angular cross-section each having one leg directed vertically and welded to the outer surface of the bottom flange of the adjacent channel in inwardly spaced relation to the plane of the web, means connecting said plurality of metal plates together, back stops overlapping and secured to the ends of said channels and metal plates, said back stops being held by the top and bottom flanges of said channels in a plane substantially normal to the planes of the channel webs, and buttressing means secured to said back stops and webs of said channels rearwardly of said back stops and intermediate the flanges of said channels.
